UNITED STATES PATENT OFFICE.

FREDERICK LEOPOLD, JR., OF HARMONVILLE, PENNSYLVANIA, ASSIGNOR TO LEE RUBBER & TIRE CORPORATION, OF CONSHOHOCKEN, PENNSYLVANIA, A CORPORATION OF NEW YORK.

DESIGN FOR A TIRE CASING OR SIMILAR ARTICLE.

Application filed February 7, 1927. Serial No. 20,642. Term of patent 14 years.

To all whom it may concern:

Be it known that I, FREDERICK LEOPOLD, Jr., a citizen of the United States of America, residing at Harmonville, in the county of Montgomery, and State of Pennsylvania, have invented a new, original, and ornamental Design for Tire Casings, or Similar Articles, of which the following is a specification, reference being had to the accompanying drawings, forming part thereof, in which:

Figure 1 is a plan view of my present design embodied in an automobile tire casing or similar article; and

Figure 2 is a diagrammatic, fragmentary, transverse sectional view taken on the line 2—2 of Figure 1.

It is to be understood however, that my said ornamental design is applicable not alone to casings, but is intended, and is equally well suited for the ornamentation of similar articles of manufacture having the surface ornamentation shown, without in the least departing from the spirit of my invention.

I claim:

The ornamental design for a tire casing or similar article substantially as shown and described.

In testimony whereof I subscribe my signature.

FREDERICK LEOPOLD, JR.
